GLOBE OR SHADE HOLDER

Filed May 29, 1929

INVENTOR:
NICOLA C. PETRILLO

BY *Arthur C Eckart*
ATTORNEY.

UNITED STATES PATENT OFFICE

NICOLA CESARE PETRILLO, OF ST. LOUIS, MISSOURI

GLOBE OR SHADE HOLDER

Application filed May 29, 1929. Serial No. 366,803.

The object of my device is to make a globe or shade holder to be used particularly for globes or shades for street lamps. A further object is to make a globe or shade holder that 5 will hold the shade or globe positively and prevent the breakage of the globe on account of vibration. These globes are positioned on poles and where the poles are located on viaducts or bridges or even on city streets, 10 they are subjected to varying amounts of vibration or movement. This vibration or movement fractures the globe when the ordinary globe holder is used. My device prevents the breakage from such vibration and 15 also prevents breakage incident to the removal and positioning on the holder of the globe. It is necessary to be able to remove the globe at intervals from the base or support for the purpose of cleaning the globe 20 and replacing burnt out lights. By the use of my device the globe may be easily removed and replaced without disturbing the portion of my device that comes in contact with the globe. By the use of my device the strains 25 are equalized and minimized between the metal portion of the holder and the globe. When the conventional method is employed, that is when screws come in contact with the globe, strains are set up in the glass adjacent 30 the screws, which eventually crack the glass. My globe holder may be made of few and simple parts and lends itself readily to multiple production.

With these and other objects in view my 35 invention has relation to certain novel features of construction and arrangement of parts as will be hereinafter more fully described, pointed out in the claim and illustrated in the drawings, in which

40 Fig. 1 is a front elevation of my device, showing a portion of the globe.

Fig. 2 is a plan view of my device.

Fig. 3 is a transverse median section of Fig. 2.

45 Fig. 4 is a perspective view of the split ring used in my device.

Fig. 5 is a perspective view of the gasket used in my device.

50 Numeral 6 designates the base or support for the globe, which base or support is se-

cured to the top of the pole by means of the annular depending flange 7. Numeral 8 designates the outer wall of the base 6 and numeral 9 designates an inner annular flange. Between the outer wall 8 and the inner annular flange 9 is formed the annular recess 10. The outer wall 8 is considerably higher than the inner annular flange 9. In the outer wall 8 are formed the tapped radial holes 11 into which are secured in threaded engagement the screws 12. Numeral 13 designates the globe having the annular flange 14 formed at its lower end. Numeral 15 designates a gasket, which conforms to the shape of the annular flange 14 and is of the same circumference as the annular flange 14 and is placed in contact with the annular flange 14. Numeral 16 designates a split ring, which is split into two equal arcs. At the free ends are formed the ears 17 having the tapped holes 18 passing therethrough. Numerals 19 designate screws passing through the tapped holes 18 of the ears 17. Numerals 20 designates coiled springs positioned over the screws 19 between the head and the nearest of the ears 17. The split ring 16 is placed over the gasket 15 and the screws 19 tightened against the compression of the coiled springs 20. On the split ring 16 are formed the lugs 21, which extend radially outward and downward from the body of the split ring 16. The split ring is shown in its inverted position in Fig. 4. Numerals 22 indicate slots formed in the lugs 21. There are four such lugs 21 shown in Fig. 2. In assembling after the split ring 16 has been secured as shown in Fig. 3 to the globe 13, the split ring is placed on the base 6, so that the lugs 21 extend downwardly in sliding engagement on the outer wall 8. The screws 12 are so positioned that by turning the split ring 16 through a small arc, the slots 22 of the lugs 21 will pass over the shanks of the screws 12 under the heads of the screws 12. In this position the screws 12 are screwed down tightly thereby securing the split ring 16 firmly to the base 6.

It will be seen that when the post, on which the globes are mounted is vibrated, a slight vibration of the globe is permitted within the split ring 16 against the compression of the

coiled springs 20. This movement is extremely slight, but is sufficient to prevent the breaking or fracture of the globe.

What I claim and mean to secure by Letters Patent is:

5 A base having an outer wall, screws in threaded engagement in said outer wall, a split ring positioned on said base, said split ring having lugs formed thereon with slots 10 formed therein for engagement with said screws, said split ring being composed of segments having ears at their free ends with threaded holes passing therethrough, screws in threaded engagement in the holes in the 15 lugs formed on said split ring, a coiled spring secured on said screws between the head and the adjacent ears of said split ring, a globe, a gasket secured to said globe, said gasket in frictional engagement with said split ring.

20 In testimony whereof I affix my signature.

NICOLA CESARE PETRILLO.
